(57) **CLAIM**

The ornamental design for an article hanger, as shown and described.

DESCRIPTION

FIG. 1 is a front right side perspective view of the article hanger of the present invention;

FIG. 2 is a front view thereof;

FIG. 3 is a rear view thereof;

FIG. 4 is a bottom view thereof;

FIG. 5 is a top view thereof; and,

FIG. 6 is a left side view thereof.

The broken lines represent portions of the structure that forms no part of the claim.
